United States Patent Office

Des. 188,453
Patented July 26, 1960

188,453

COMBINED SOAP DISH AND TRAY

William Marcus, Cleveland, Ohio, assignor to The Stand-fast Products Company, Cleveland, Ohio, a corporation of Ohio

Filed Nov. 5, 1959, Ser. No. 58,212

Term of patent 14 years

(Cl. D4—3)

Fig. 1

Fig. 2

Fig. 3

The dominant features of my design reside in the full-line portions of the drawing.

I claim:

The ornamental design for a combined soap dish and tray, as shown and described.
